ARRANGEMENT FOR CONVERTING DIRECT CURRENT INTO ALTERNATING CURRENT BY MEANS OF ELECTRIC VACUUM VALVES

Application filed December 14, 1928, Serial No. 326,050, and in Switzerland December 16, 1927.

This invention relates to the conversion of direct current into alternating current by means of electric vacuum valves.

The invention has more particular reference to an arrangement wherein two or more vacuum valves are rendered conductive by intermittent regular ionization effected only during a fraction of the conductive period of said valves, the arrangement being such that the conductivity of one vacuum valve is interrupted by a back electromotive force set up between the cathode and anode of said valve by virtue of the regular ionization of a second vacuum valve having its cathode connected with the cathode of said first valve and with the negative pole of the direct current source and its anode connected with a point of the primary winding of a transformer which is momentarily at a higher potential than the anode of said first valve.

In order that at the moment of ionization of the valve having the higher anode potential a relatively larger current may be produced for quenching the valve having the lower anode potential which does not pass through the primary winding of the transformer, the arrangements above mentioned may include condensers which are inserted in parallel with the vacuum valves and are also adapted to influence the temporary increase and decrease of current in said primary winding at the moment of ionization and of quenching respectively of the valves.

One object of the invention is to produce quenching of said valves without the necessity of providing special quenching condensers in an arrangement as above mentioned.

A further object of the invention is to provide means for producing a capacitative quenching current.

These and other objects will be clearly seen from the following description read in conjunction with the attached drawing on which:—

Fig. 1 shows diagrammatically one arrangement for converting direct current into alternating current.

Fig. 2 shows diagrammatically a modified

arrangement provided with safety cut out devices.

Referring to Fig. 1, T denotes the main transformer, with the primary winding P and secondary winding S, V₁ and V₂ the vacuum valves, A₁ and A₂ their main anodes, Z₁ and Z₂ their ionizing anodes, K₁ and K₂ their cathodes, Q the source of direct current and D a choke. Furthermore, C₁ and C₂ denote the condensers which are connected in parallel with the vacuum valves, each being connected to a separate winding of an auxiliary transformer T'. R₁ and R₂ are resistances by means of which the condenser currents can be rendered aperiodic. Assuming that, at a given moment, the valve V₁ is conductive and the valve V₂ is non-conductive, the condenser C₁ is then short-circuited through the valve V₁, whilst the condenser C₂ is charged to the potential of the anode A₂. If now the valve V₂ be energized through the ionizing anode Z₂, and thereby rendered conductive, the condenser C₂ will discharge through the valve V₂, and this discharge current induces (through the transformer T') in the circuit of the condenser C₁, a quenching current which quenches the valve V₁. On the potential rising at the anode A₁ the condenser C₁ becomes charged. If now the valve V₁ be energized through the ionizing anode Z₁, the operations described with reference to V₂ are repeated in the valve V₁, whilst the valve V₂ is now quenched by the current quenching induced in the circuit of the condenser C₂. The rhythmic ionizing of the valves V₁ and V₂ is thus at the same time accompanied by a rhythmic quenching of the valves V₁ and V₂.

This arrangement can also be employed for interrupting the current conversion, which interruption can be effected automatically on a certain maximum current being exceeded, or on the direct current suddenly rising above a permissible limit as the result of a short circuit; or it may be effected by a hand-operated switch. With this object, the transformer T' is provided with a third winding, which is traversed by the direct current to be converted, a portion of same being short-circuited through a switch which is opened,

either by the direct current to be converted, when a given maximum is exceeded, or by an auxiliary circuit which is closed by a hand switch. Opening of this switch, suddenly increases the value of the ampere-turns of the direct current winding of the transformer T' , thereby inducing, in the circuits of both the condensers in parallel with the valves, a quenching voltage, so that the valve which is conductive at the moment is quenched. The case is the same when the direct current suddenly rises as the result of a short-circuit. In order also to interrupt the ionization and prevent a fresh ionization, there is connected in the direct current circuit a second auxiliary transformer, the direct current winding of which is also partially short-circuited through the aforesaid switch. The secondary current induced in this second auxiliary transformer by a rapid change of field quenches an auxiliary vacuum valve disposed in the common return lead of the ionizing current serving for the rhythmic ionization of the main vacuum valves, so that such rhythmic ionization is interrupted. A typical embodiment of this arrangement is shown in Fig. 2 in which the same parts are denoted by the same reference characters as in Fig. 1. T' is the auxiliary transformer with three windings, the third winding being traversed by direct current whilst the other two are connected to the condensers C_1 and C_2 . T'' is a secondary auxiliary transformer, one winding of which is traversed by direct current, whilst the other is connected to a condenser C_3 which serves to quench an auxiliary vacuum valve V^3 . 1 and 2 are ionizing current leads, whilst 3 is the common return lead, in which is interposed the auxiliary vacuum valve V^3 , having an anode A^3 , cathode K^3 and an ionizing anode Z_3 . Ordinarily, this auxiliary valve is maintained in a conductive state by a source Q_1 of direct current.

If the value of direct current ampere-turns in the auxiliary transformers T' and T'' is suddenly increased, whether by a short-circuit, or by opening the switch Sch by means of a direct current solenoid Sp_1 , or by a trip solenoid Sp_2 (by actuating a hand switch H), voltages or currents are induced in the secondary windings of these transformers and quench the main valves V_1 , V_2 and the auxiliary valve V^3 , through the condensers C_1 , C_2 , C_3 .

D_1 is a choked coil, the value of which is such that neither any appreciable portion of the ionizing current impulse nor of quenching current impulse can pass therethrough.

In the rhythmic quenching of the main valves, although a voltage is also induced in the direct current winding of the auxiliary transformer T' ; nevertheless, since at such moment the quenching circuit is short circuited through the conductive vacuum valve,

the greater portion of the induced energy will be thereby absorbed, especially since the inductances of the main transformer T and the choke coil D are operative in the direct current circuit.

I claim:—

1. That improvement in the art of converting direct current into alternating current by means of two electric vacuum valves each alternately submitted to regular ionization which sets up a back electromotive force between the cathode and the anode of said other valve to quench said other valve and to interrupt the conductivity thereof which consists in inserting a condenser in parallel with each of said valves and coupling the condenser circuits together so that the discharge current of one condenser at the moment of ionization of said vacuum valve in parallel therewith sets up a quenching current in the condenser circuit of said other vacuum valve. 70 75 80 85

2. That improvement in the art of converting direct current into alternating current by means of two electric vacuum valves each alternately submitted to regular ionization which sets up a back electromotive force between the cathode and the anode of said other valve to quench said other valve and to interrupt the conductivity thereof which consists in inserting a condenser in parallel with each of said valves and utilizing the discharge current of one condenser at the moment of ionization of said vacuum valve in parallel therewith to induce a quenching current for said other vacuum valve in the condenser circuit of said other vacuum valve. 90 95 100

3. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves, a condenser connected in parallel with said first vacuum valve, a condenser connected in parallel with said second vacuum valve and inductive means coupling said condenser circuits. 105 110 115

4. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves 120 125 130

to the negative pole of said source, separate ionizing anodes for each of said valves, a condenser connected in parallel with said first vacuum valve, a condenser connected in parallel with said second vacuum valve and an auxiliary transformer having one winding connected in series with one condenser and another winding connected in series with said other condenser.

10 5. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves, a condenser connected in parallel with said first vacuum valve, a condenser connected in parallel with said second vacuum valve and an auxiliary transformer having one winding connected in series with one condenser, another winding connected in series with said other condenser and a third winding connected in series with said source of direct current and adapted on passage of an overload current through said third winding to induce a quenching current in each of said condenser circuits for the simultaneous quenching of said vacuum valves.

6. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves, a condenser connected in parallel with said first vacuum valve, a condenser connected in parallel with said second vacuum valve, an auxiliary transformer having one winding connected in series with one condenser, another winding in series with said other condenser, and a third winding in series with said source of direct current and means to increase the ampere turns of said third winding to induce in said other windings a quenching current adapted to quench said valves.

7. An arrangement for converting direct current into alternating current which comprises a transformer having a primary and a secondary winding, a source of direct current having its positive pole connected to

the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves a condenser connected in parallel with said first vacuum valve, a condenser connected in parallel with said second vacuum valve, an auxiliary transformer having one winding connected in series with one condenser, another winding in series with said other condenser, and a third winding in series with said source of direct current and means responsive to an overload current through said source of direct current to increase the ampere turns of said third winding to induce in said other windings a quenching current adapted to quench said valves.

8. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves, a condenser connected in parallel with said first vacuum valve, a condenser connected in parallel with said second vacuum valve and an auxiliary transformer having one winding connected in series with one condenser, another winding connected in series with said other condenser and a third winding connected in series with said source of direct current and adapted on passage of an overload current through said third winding to induce a quenching current in each of said condenser circuits for the simultaneous quenching of said vacuum valves and means in said cathode connections of said valves to prevent renewed ionization of said valves.

9. An arrangement for converting direct current into alternating current which comprises a transformer having a primary and a secondary winding, a source of direct current having its positive pole connected to the mid point of said primary winding, a vacuum valve having its anode connected to one end of said primary winding, a second vacuum valve having its anode connected to the opposite end of said primary winding, means connecting the cathode of each of said vacuum valves to the negative pole of said source, separate ionizing anodes for each of said valves, a condenser connected in par- 130

allel with said first vacuum valve, a condenser connected in parallel with said second vacuum valve and an auxiliary transformer having one winding connected in series with one condenser, another winding connected in series with said other condenser and a third winding connected in series with said source of direct current and adapted on passage of an overload current through said third winding to induce a quenching current in each of said condenser circuits for the simultaneous quenching of said vacuum valves, an auxiliary vacuum valve maintained in a conductive state interposed in said common cathode, connection of said vacuum valves, an auxiliary condenser connected in parallel with said auxiliary vacuum valve and a second auxiliary transformer having one winding in series with said source of direct current and another winding in series with said auxiliary condenser and adapted on increase of the ampere turns of said one winding to induce a quenching current in said auxiliary condenser circuit adapted to quench said auxiliary vacuum valve.

In testimony whereof, I affix my signature.
